[57] CLAIM

The ornamental design for a combined fireplace insert front panel and trim, as shown and described.

DESCRIPTION

FIG. 1 is a perspective view of a combined fireplace insert front panel and trim showing our new design;

FIG. 2 is a top plan view thereof;

FIG. 3 is a front elevational view thereof;

FIG. 4 is a left side elevational view thereof, the right side being a mirror image of that shown; and

FIG. 5 is a bottom plan view thereof.
